UNITED STATES PATENT OFFICE.

WILLIAM ROBERT MEDEARIS, OF NASHVILLE, TENNESSEE.

BACK-BAND BUCKLE.

SPECIFICATION forming part of Letters Patent No. 789,043, dated May 2, 1905.

Application filed March 18, 1904. Serial No. 198,792.

To all whom it may concern:

Be it known that I, WILLIAM ROBERT MEDEARIS, a citizen of the United States, residing at Nashville, in the county of Davidson and State of Tennessee, have invented a new and useful Improvement in Back-Band Buckles, of which the following is a specification.

My invention relates to an improvement in that class of back-band buckles in which a front or face plate slides on a rear or base plate to form a closure for the hook which carries the trace-chain.

The object of my invention is to provide a combined back-band buckle and trace-carrier which shall be simple in construction, efficient in operation, easily manipulated, and which can be made from a very small amount of material.

To these ends my invention consists in certain novel features of construction, combination, and arrangement of parts, as will be hereinafter fully described, and pointed out in the claims, reference being had to the accompanying drawings, in which—

Figure 1 is an elevation showing one form of buckle. Fig. 2 is a sectional view of Fig. 1, taken on line 2 2 of Fig. 1. Fig. 3 is an elevation showing another form of buckle. Fig. 4 is a sectional view on line 4 4 of Fig. 3. Fig. 5 is a view of buckle made entirely of wire. Fig. 6 is a sectional view on line 6 6 of Fig. 5. Fig. 7 is a view of a modification.

Referring now to the several figures of the drawings, A is the base or rear plate, provided at its lower end with a downwardly-projecting and upwardly-turned hook member A' and having the slot A² in its body portion. At or near the junction of the hook member and the body portion are the inwardly-projecting ears or guides A³, which project toward each other, as shown.

B is the front or face plate, provided with the slot B' in its body portion and having a downwardly-projecting tongue or extension B², which is bent or turned outwardly at substantially a right angle to form the guard or keeper B³, the purpose of which will be presently set forth.

In assembling the parts to make a complete buckle the tongue or extension B² of plate B

is slid into place between the ears or guides A³ of the base-plate A. The tongue B² is preferably provided with a hump or swell B⁴, said tongue in its central portion B⁵ being bent rearwardly to lie against the front face of the base-plate. The purpose of the hump or swell is to cause the two plates to bind snugly against each other when the front plate is slid downwardly and hold the guard or keeper B³ securely against the upper end of the hook A'. The webbing of the back-band is passed through the slots in the two plates and then drawn to the desired adjustment. By pushing guard or keeper B³, the end of which projects slightly beyond the front face of the hook, said hook is opened and the trace-chain can be readily placed in said hook. The guard is then pushed downwardly again until it rests on the end of the hook, thus forming a closure for the same and a loop in which the trace-chain rests.

The two members of combined buckle and trace-carrier can be made entirely of sheet metal or one of sheet metal and the other of wire, or they can both be made of wire, as shown in Figs. 5 and 6 of the drawings.

A simple and cheap form of my device can be made as shown in Fig. 7, in which form the ears or guides are omitted and the tongue of the face-plate slides within the hook. In this form the sole connecting means for the two members of the buckle is the webbing of the back-band passed through the respective slots of the two plates.

The construction of my improved buckle is such that when the web is inserted in the slots and pulled down in position there is no chance for the web to slip, because the ears or guides on the base-plate within which the face-plate slides holds both members of the buckle tightly together, making a clamp on the web. Furthermore, there is no liability of the link of the trace-chain getting out of the hook, because the said hook is entirely closed by the guard or keeper and will remain so until said guard is forced upwardly by hand.

It will be seen that this combined back-band buckle and trace-carrier is simple, cheap, easily adjusted, strong, and durable, and having no teeth will not destroy the web.

Having thus described my invention, what I claim as new, and desire to secure by Letters Patent, is—

1. A combined back-band buckle and trace-carrier, consisting of a base plate or frame having a slot in its upper portion and an upwardly-projecting hook at its lower end, ears or guides projecting from said plate below said slot, a face or front plate or frame having a slot in its upper portion, and a downwardly-projecting tongue fitted between said ears or guides and adapted to slide within said guides and abut against the hook to close the same, whereby a band or web passed through the slots of the two plates is clamped between the adjacent faces of the two plates or frames.
2. A combined back-band buckle and trace-carrier, consisting of a base plate or frame having a slot in its upper portion and an upwardly-turned hook at its lower end, ears or guides projecting from the side edges of said plate inwardly over the face thereof below the said slot, a face plate or frame having a slot in its upper portion and a downwardly-projecting tongue member extending from the body of said face-plate between the said ears or guides of the base-plate, the lower end of said tongue bent outwardly at an angle and adapted to abut against the upper end of the

upturned hook of the base-plate and close the same, whereby when a band or web is passed through the slots of the two plates, it will be clamped between the adjacent faces of said base and face plates.

3. A combined back-band buckle and trace-carrier, comprising a base plate or frame having a slot in its upper portion and an upwardly-turned hook at its lower end, ears or guides projecting from the side edges of said plate and extending inwardly over the front face of the same, a front or face plate having a slot in its upper portion, a tongue projecting downwardly from said plate and fitted between the ears or guides on the base-plate, an outwardly-bent guard at the lower end of the tongue adapted to close the hook when in operative position, said tongue also provided with a hump or curved portion which engages the inner faces of the ears or guides when said guard is forced downwardly, and forces the base and face plates or frames closely together, whereby a band or web passed through the slots in said plates will be securely clamped between said plates or frames.

WILLIAM ROBERT MEDEARIS.
